UNITED STATES PATENT OFFICE.

FREDERICK A. BAUM, OF ST. CHARLES, MISSOURI.

MACHINE FOR STEAMING THE TOES OF SHOES.

1,357,023.

Specification of Letters Patent.

Patented Oct. 26, 1920.

Application filed June 17, 1919. Serial No. 304,751.

To all whom it may concern:

Be it known that I, FREDERICK A. BAUM, a citizen of the United States, residing at St. Charles, in the county of St. Charles, 5 State of Missouri, have invented certain Improvements in Machines for Steaming the Toes of Shoes, of which the following is a specification.

This invention relates to apparatus for 10 subjecting the toe portion of a boot or shoe to the action of moist heat prior to the pulling over or lasting operations, or both, in order to prevent the cracking of the leather during said operations, and the 15 prime object of the invention is to provide (a) means for insuring an even distribution of hot vapor over the entire toe, (b) means for controlling the degree of heat applied to the toe so as to prevent damage to the 20 leather and (c) means for insuring that the heat delivered to the toe will not be excessively moist.

Other objects and advantages will become 25 apparent upon consideration of the following portions of the specification and the appended claims.

Referring to the drawing, wherein like numerals refer to like parts throughout, Figure 1 is a front elevation of the complete 30 machine and Fig. 2 is a sectional elevation taken along line 2—2 of Fig. 1.

In carrying the invention into practice, I provide a substantially rectangular metal lined box or tank 1, which may be supported above the floor upon a pedestal 2 or in any other manner found desirable. A steam supply pipe 3 is projected horizontally through the lower portion of the box and provided with a plurality of small vents 4 35 permitting the escape of steam into the water which ordinarily is maintained at substantially the level shown in Fig. 2. A glass gage 5 mounted upon valve housing 6 serves to indicate any variation in the water 40 level, said housing being provided with a pipe 7 and a drain 8 controlled by cock 9 affording means for lowering the water level as occasion may demand or draining the tank when necessary, while the upper end 45 of said gage is surmounted with a pipe 10 communicating with the interior of the tank above the water level and thus serving to prevent the formation of a vacuum within the glass. An overflow pipe is indicated 50 at 11.

Within the tank and extending from side to side thereof is an inverted U-shaped member 12 providing a chamber 13 for the storage of the hot vapor arising from the water, said member having a plurality of 60 oblong ports 14 for the escape of said vapor which then passes through narrow slots 15—16 extending substantially from end to end of metal partition 17.

The upper edge of the front wall of box 65 1 is cut away for the reception of a plurality of perforate concave plates 18 adapted to accommodate the toe portion of a shoe and disposed above said plates are covered members 19 provided with lugs 20 which are engaged by pivots 21 so that said covers may be swung rearwardly to permit the free circulation of air about the toe when it is found that the latter is being excessively heated.

The toe portion of the shoe is positioned 75 at any desired height relative to the bottom of plates 19 by adjustment of wooden or fiber slides 22 which are retained against the bottom wall of box 1 by wing-nuts 23 projecting through slots 24 and the heel portion of the shoe is disposed within substantially V-shaped members 25 extending laterally from plate 26 supported by bracket 27 and slotted longitudinally so that it may be adjusted horizontally upon release of 80 wing-nut 28. The lower portion of bracket 27 is also provided with a slot 29, whereby it may be adjusted vertically upon release of nut 30 so that the operator may raise or lower the heel portion of the shoe to correspond with the adjustment of slides 23.

In operation, a shoe ready to be lasted is positioned with its toe extending within plate 18 and resting upon the upper edge of slide 22. Steam is continuously injected 95 through vents 4 of pipe 3 and the water thus brought to a high temperature throws off vapor which accumulates within chamber 13 and passes thence through ports 14 of member 12 to the space beneath partition 17, the latter becoming sufficiently hot to convert a percentage of the moisture into steam so that the vapor escaping through slots 15—16 and reaching the toe of the shoe through the perforations of plates 18 is 100 fairly dry as compared with the vapor supplied by similar machines of the prior art. Having been subjected to this treatment for several minutes, the toe will be sufficiently heated and moistened to enable the 105 110

operator to perform the lasting operation easily and with little danger of cracking the leather.

The use of perforate plates 18 is considered a distinct advance in the art in that I thus insure an even distribution of the hot vapor over the entire surface of the toe and maintain said vapor at an even temperature by greatly restricting the passage 10 of air to the interior of the box.

Having thus fully described the invention, what I claim as new and desire to secure by Letters-Patent is:—

1. A machine of the character described, comprising a box having apertures in one of its walls each thereof adapted to admit the toe of a shoe, means for supporting the toe and heel portions of the shoe, a steam supply pipe projecting within said box adjacent to the bottom thereof, and perforate plates disposed opposite said apertures, said plates being curved, substantially as shown, so as to substantially inclose said toe.

2. A machine of the character described, comprising a box having apertures in one of its walls each thereof adapted to admit the toe of a shoe, a steam supply pipe projecting within said box adjacent to the bottom thereof, devices for supporting the heel portion of the shoe, means for raising or lowering said devices, and means for adjusting said devices simultaneously relative to each of said apertures to accommodate shoes of different lengths.

3. A machine of the character described, comprising a box having apertures in one of its walls each thereof adapted to admit the toe of a shoe, a steam supply pipe projecting within said box adjacent to the bottom thereof, adjustable means for supporting the toe at various heights relative to the base of said apertures, devices for supporting the heel portion of the shoe, means for raising or lowering said devices, and means 45 for adjusting said devices to accommodate shoes of different lengths.

4. A machine of the character described, comprising a box having apertures in one of its walls each thereof adapted to admit the toe of a shoe, a steam supply pipe projecting within said box adjacent to the bottom thereof, perforate plates disposed opposite said apertures, said plates being curved, substantially as shown, so as to sub-

tantly inclose said toe, and a slotted partition disposed beneath said plates.

5. A machine of the character described, comprising a box having apertures in one of its walls each thereof adapted to admit the toe of a shoe, a steam supply pipe projecting within said box adjacent to the bottom thereof, perforate plates disposed opposite said apertures, said plates being curved, substantially as shown, so as to substantially inclose said toe, and an inverted 65 substantially U-shaped member disposed above said pipe provided with a plurality of ports.

6. A machine of the character described, comprising a box having apertures in one of its walls each thereof adapted to admit the toe of a shoe, a steam supply pipe projecting within said box adjacent to the bottom thereof, a slotted partition disposed between said pipe and said apertures, and an 75 inverted substantially U-shaped member disposed beneath said partition having a plurality of ports.

7. A machine of the character described, comprising a box having apertures in one of its walls each thereof adapted to admit the toe of a shoe, a steam supply pipe projecting within said box adjacent to the bottom thereof, perforate plates disposed opposite said apertures, said plates being 85 curved, substantially as shown, so as to substantially inclose said toe, a slotted partition disposed beneath said plates, and an inverted substantially U-shaped member disposed beneath said partition having a 90 plurality of ports.

8. A machine of the character described, comprising a box having apertures in one of its walls each thereof adapted to admit the toe of a shoe, means for supporting the 95 toe and heel portions of the shoe, a steam supply pipe projecting within said box adjacent to the bottom thereof, perforate plates disposed opposite said apertures, said plates being curved, substantially as shown, so as to substantially inclose said toe, and members hingedly mounted above said plates adapted to control the admission of air to the box.

FREDERICK A. BAUM.
